CLAIM

The ornamental design for a bottle cover, as shown and described.

DESCRIPTION

FIG. 1 is a rear, left and top perspective view of a bottle cover, showing my design.

FIG. 2 is a front, right and top perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken away symbols in the drawings indicate that any portion of the article beyond what is shown forms no part of the claimed design.

The broken lines shown in the drawings are included for the purpose of illustrating portions of the bottle cover that form

(Continued)

no part of the claimed design. The dot-dash lines represent the boundaries of the claim and form no part thereof.

1 Claim, 8 Drawing Sheets
